UNITED STATES PATENT OFFICE.

VINCENT BENDIX, OF CHICAGO, ILLINOIS.

ENGINE-STARTER.

1,327,304.

Specification of Letters Patent.

Patented Jan. 6, 1920.

Application filed March 31, 1919. Serial No. 286,387.

To all whom it may concern:

Be it known that I, VINCENT BENDIX, a citizen of the United States, residing at Chicago, in the county of Cook and State 5 of Illinois, have invented certain new and useful Improvements in Engine-Starters, of which the following is a specification.

My invention relates to a starter for an engine such as an internal combustion engine and the object thereof is to produce an automatic drive or transmission therefor of novel and efficient construction and mode of operation.

My new construction of drive belongs to 15 that general type as exemplified by patents heretofore issued to me such as Patent No. 1,125,935 dated January 26, 1915, and No. 1,274,370 dated August 6, 1918, according to which a driving member, whether the 20 pinion itself which engages the engine member such as the fly wheel or a separate member which controls such a pinion, is mounted on a rotatable shaft such as a screw shaft and automatically causes engagement of the 25 drive with and its disengagement from the engine member after the engine has started on its own power.

One of the main objects of my invention is to provide a novel and efficient construction of drive according to which the rotatable member or screw shaft is relieved of 30 the driving load and such load placed entirely upon a separate shaft which is the driven shaft and which may be directly or 35 indirectly driven by the starting motor or other source of power. The driving member may be rather closely fitted upon the screw shaft and is adapted to be operatively connected therewith upon full mesh thereof 40 with the engine member. My invention relates more particularly to the construction of this driving member according to which the same is made in three parts, one being the driven member proper or pinion mounted 45 upon another part or sleeve and having a yielding longitudinal movement thereon.

This second part or sleeve is mounted upon an inner sleeve which is itself mounted upon the driving shaft and connected by yielding 50 driving connection with the second mentioned sleeve. According to this construction the driving member is yieldingly driven and also permitted a yielding longitudinal movement in case of abutment of the pinion 55 teeth and fly wheel teeth end to end.

In the drawing Figure 1 is a sectional elevation of a starter embodying my invention and Fig. 2 a section on the line 2-2 of Fig. 1.

Referring to the particular embodiment 60 of my invention which is herein shown and which is selected for the purpose of a clear and definite description, it will be understood that my invention may be embodied in different forms and moreover while the 65 drive is shown as direct-driven by a starting motor, the same may be indirect-driven or the same may be driven by any suitable source of power.

As shown, the driving shaft 1 is here the 70 extended armature shaft of a starting motor indicated at A and the drive is therefore in this instance direct-driven. Upon the inner end of this shaft there is secured in suitable manner, as by a key 2 a gear 3 so as to rotate therewith. Also it will be understood that my invention while herein shown as that of the inboard type is also applicable to the outboard type. This driving shaft is 75 smooth and on it is mounted the driving 80 member which is of the following novel construction:

As shown, an extended sleeve 4 is mounted to slide longitudinally on the shaft 1 and on this sleeve there is mounted an outer sleeve 85 5 which is yieldingly drivingly connected to the inner sleeve as by means of the coiled drive spring 6 one end of which is connected to the outer end of the sleeve 4 by the stud 7 and the other end of which is 90 connected to the outer end of the outer sleeve 5 by the stud 8. If desired a clearance space 9 may be provided between the outer end of the sleeve 5 and the shoulder 10 of the sleeve 4 so that the former sleeve 95 may have a longitudinal yielding movement with respect to the latter sleeve. However, this is not necessary because the relative longitudinal movement of these parts is in the opposite direction, that is extends the 100 drive spring.

Upon the inner end portion of the sleeve 5 there is mounted the driving member proper which is here in the form of a pinion 11. This pinion is connected with the sleeve 105 5 by the key 12, with the result that such pinion will rotate in unison with its sleeve and be movable longitudinally thereon against the tension of the coiled spring 13 bearing constantly against it. The pinion 110

is limited in its longitudinal movement enforced by this spring by means of the stop nut 14 which screws into the inner bore of the sleeve 5 and the flange of which forms a stop shoulder for the pinion.

The sleeve 5 is provided intermediate its length with a gear of the shroud type. According to the present construction this gear is formed by a gear ring 15 fitted between 10 the flange 16 on the sleeve and the annulus 17, said parts being secured together by the screws 18.

The forward or left hand end of the sleeve 4 is provided with inclined clutch jaws 19 15 adapted to engage complementary clutch jaws 20 formed on the outer end of the hub 3^a of the gear 3.

Referring to the automatic shifting means for the driving member, the same is mounted 20 entirely independently of the driving shaft and its associated parts described, the same being mounted on an axis parallel to the driving shaft axis. As shown, this shifting means consists of a rotatable shaft operatively connected with the driving shaft 25 and a control member or gear co-operating with the driving member. This shaft 21, which is a countershaft with respect to the shaft 1, is suitably mounted, the same in the present instance being mounted at its ends in bearings 22 and 23 in a casing or bracket 24. To the inner end of this shaft is secured a gear 25 which is in constant mesh with the gear 3 whereby the countershaft is 30 rotated whenever the driving shaft is rotated. The countershaft is provided at its intermediate portion with screw threads 26 on which is threaded the control member, which is here in the form of a gear 27 engaged by 35 the shroud gear 15 and in such manner as to rotate in unison therewith and also shift the gear 15 and the driving member longitudinally on the driving shaft.

Describing a cycle of operation and starting 40 with the parts in their normal position shown in the drawing, when the motor is operated and the driving shaft thereby rotated, the countershaft will be similarly rotated, with the result that the gear 27 will 45 be automatically advanced longitudinally to the left, carrying with it the driving member and sliding it along the driving shaft. This causes a meshing of the pinion 11 with the teeth 28^a of the fly wheel 28. When this 50 pinion is in full mesh therewith the clutch jaws 19 and 20 will engage and the pinion will be driven by the driving shaft through 55 said clutch, sleeve 4, drive spring 6 and sleeve 5, whereby the fly wheel will be rotated and the engine started. When the 60 engine has started on its own power the excess speed of rotation thereof will cause the gear 27 to be moved backwardly to its normal position along the screw-threaded portion of the countershaft, retracting with it

the driving member which thus becomes disengaged from the fly wheel.

The load is thus carried entirely through the driving shaft and the immediately associated parts composing the driving member, 70 and no driving load is carried by the countershaft.

In the event that the pinion teeth and the fly wheel teeth should not register but such teeth should abut end to end, the force of 75 the impact is taken by the comparatively light pinion which will be thus momentarily stopped in its longitudinal movement, while the sleeve 5 will continue to advance longitudinally, said relative movement of these 80 parts being permitted by the described mounting of the pinion and being resisted by the spring 13. This stopping of the pinion will cause the gear 27 to rotate slightly thereby rotating the sleeve 5 and the pinion, 85 sufficient to bring such pinion into proper register with the fly wheel teeth.

If desired means may be employed for holding the gear 27 in the retracted or disengaged position while its shaft may still be 90 rotating. These means comprise a pin or rod 29 mounted to slide transversely through the shaft 21 and yielding held in normal position by the coiled spring 30. This pin has two lateral parallel arms 31, 31 in which 95 is mounted to slide a spring-pressed latch 32. When the shaft 21 is rotating the latch end of this device, which is the heavier end, will move outwardly by centrifugal force and will thereby present the latch to the 100 flange 33^a of a shell 33 which is secured to the hub 27^a of the screw shaft. After the countershaft has come to rest the catch device will assume its normal position shown and leave the gear 27 free to be advanced 105 longitudinally for the next starting operation.

I claim:

1. In an engine starter, a drive comprising a driving shaft, driving means mounted thereon for longitudinal movement thereof to engage a member of the engine to be started and for rotary movement therewith for rotating such engine member, and shifting means mounted extraneous of such shaft and co-operating with the driving means to control the engaging and disengaging movements thereof, said driving means including an independently longitudinally movable driving member which engages such engine member.

2. In an engine starter, a drive comprising a driving shaft, driving means mounted thereon for longitudinal movement thereof to engage a member of the engine to be 125 started and for rotary movement therewith for rotating such engine member, and shifting means mounted extraneous of such shaft and co-operating with the driving means to control the engaging and disengaging move- 130

- ments thereof, said driving means including a driving member which engages such engine member and which is mounted for a yielding longitudinal movement independent of the remainder of such driving means.
3. In an engine starter, a drive comprising a driving shaft, driving means mounted thereon for longitudinal movement thereof to engage a member of the engine to be started and for rotary movement therewith for rotating such engine member, and shifting means mounted extraneous of such shaft and coöperating with the driving means to control the engaging and disengaging movements thereof, said driving means including a pinion mounted for a yielding longitudinal movement independent of the remainder of such driving means.
4. In an engine starter, a drive comprising a driving shaft, driving means mounted thereon for longitudinal movement thereof to engage a member of the engine to be started and for rotary movement therewith for rotating such engine member, and shifting means mounted extraneous of such shaft and coöperating with the driving means to control the engaging and disengaging movements thereof, such driving means including a sleeve slidable on the shaft and adapted to be drivenly connected therewith upon its advance longitudinal movement, a second sleeve mounted on the first sleeve and operatively connected therewith, and an independently longitudinally movable driving member which is mounted on the second sleeve and engages the engine member.
5. In an engine starter, a drive comprising a driving shaft, driving means mounted thereon for longitudinal movement thereof to engage a member of the engine to be started and for rotary movement therewith for rotating such engine member, and shifting means mounted extraneous of such shaft and coöperating with the driving means to control the engaging and disengaging movements thereof, such driving means including a sleeve slidable on the shaft and adapted to be drivenly connected therewith upon its advance longitudinal movement, a second sleeve mounted on the first sleeve and operatively connected therewith, and a pinion which engages the engine member and which is splined on the second sleeve for independent longitudinal movement thereon.
8. In an engine starter, a drive comprising a driving shaft, driving means mounted thereon for longitudinal movement thereof to engage a member of the engine to be started and for rotary movement therewith for rotating such engine member, and shifting means mounted extraneous of such shaft and coöperating with the driving means to control the engaging and disengaging movements thereof, such driving means including a sleeve slidable on the shaft and adapted to be drivenly connected therewith upon its advance longitudinal movement, a second sleeve mounted on the first sleeve and operatively connected therewith, and an independently longitudinally movable driving member which is mounted on the second sleeve and engages the engine member, said second sleeve being geared to said shifting means.
9. In an engine starter, a drive comprising a driving shaft, driving means mounted thereon for longitudinal movement thereof to engage a member of the engine to be started and for rotary movement therewith for rotating such engine member, shifting means mounted extraneous of such shaft and coöperating with the driving means to control the engaging and disengaging movements thereof, such driving means including a sleeve slidable on the shaft and adapted to be drivenly connected therewith upon its advance longitudinal movement, a second sleeve mounted on the first sleeve and operatively connected therewith, and an independently longitudinally movable driving member which is mounted on the second sleeve and engages the engine member, said second sleeve being geared to said shifting means.
6. In an engine starter, a drive comprising a driving shaft, driving means mounted thereon for longitudinal movement thereof to engage a member of the engine to be started and for rotary movement therewith for rotating such engine member, shifting means mounted extraneous of such shaft and coöperating with the driving means to control the engaging and disengaging movements thereof, such driving means including a sleeve slidable on the shaft and adapt-

1
second sleeve having a shroud gear and said shifting means having a shiftable gear engaging such shroud gear.

10. In an engine starter, a drive comprising a driving shaft, driving means mounted thereon for longitudinal movement thereof to engage a member of the engine to be started and for rotary movement therewith for rotating such engine member, shifting means mounted extraneous of such shaft and coöperating with the driving means to control the engaging and disengaging movements thereof, such driving means including a sleeve slidable on the shaft and adapted to be drivenly connected therewith upon its advance longitudinal movement, a second sleeve mounted on the first sleeve and operatively connected therewith, and an independently longitudinally movable driving member which is mounted on the second sleeve and engages the engine member, said second sleeve carrying such driving member at one end and being connected at its other end to the first sleeve, and being geared

at an intermediate portion to said shifting ²⁵ means.

11. In an engine starter, a drive comprising a driving shaft, driving means mounted thereon for longitudinal movement thereof to engage a member of the engine to be started and for rotary movement therewith for rotating such engine member, and shifting means mounted extraneous of such shaft and coöperating with the driving means to control the engaging and disengaging movements thereof, such driving means including a sleeve slidable on the shaft and adapted to be drivenly connected therewith upon its advance longitudinal movement, a second sleeve mounted on the first sleeve and ³⁰ operatively connected therewith, a coiled spring forming such operative connection, and an independent longitudinally movable driving member which is mounted on the second sleeve and engages the engine member. ³⁵

VINCENT BENDIX.
